UNITED STATES PATENT OFFICE.

JOHN J. HOFFMAN, OF GLEN COVE, NEW YORK, ASSIGNOR OF THREE-FOURTHS TO WALTER E. DURYEA, OF SAME PLACE.

PAPER BOX.

SPECIFICATION forming part of Letters Patent No. 508,570, dated November 14, 1893.

Application filed February 13, 1893. Serial No. 462,043. (No model.)

To all whom it may concern:

Be it known that I, JOHN J. HOFFMAN, of Glen Cove, in the county of Queens and State of New York, have invented a new and useful Improvement in Paper Boxes, of which the following is a specification.

This invention relates to that class of paper boxes known as knock-down boxes which consist of a tube of stout paper having at each end an attached lining strip of thinner paper which is folded in to constitute the closure at the top and bottom of the box. In such a box as heretofore commonly constructed, the tube has been slitted or notched at the corners for some distance from each end and creased transversely between the slits to form flaps which have to be turned inward at right angles in closing the ends of the box, and the lining strips are pasted or attached only to those parts of the interior of the tube beyond the corner slits or notches and transverse creases which form the flaps, the so attached lining strips being left free from or unattached to the flaps so that they may be folded in before and independently of the flaps, which latter are made deep or long enough to overlap each other over the folded-in lining strip.

According to my invention I paste or attach the lining strip not only to the parts of the tube beyond the corner slits or notches but also to the flaps and I make the flaps so shallow or short and form them in such manner at the corners of the tube that they may, without overlapping each other, fold in with the lining strip and yet permit the lining strip to be folded in with as much facility as though it were free from them. By this construction I provide as good a closure for the ends of the box while I save stock in the flaps and also greatly simplify the operation of closing the ends of the box and so save time and labor in that operation.

Figure 1 is a perspective view; Fig. 2 a vertical or longitudinal section and Fig. 3 an end view of a box embodying my invention, Fig. 1 showing the bottom closed and the top partly closed, Fig. 2 showing the bottom closed and the top open and Fig. 3 showing the top or upper end closed.

A is the body of the box consisting of a paper tube of rectangular transverse section having both its ends notched at the corners as shown in the upper end at *a a* in Fig. 1, and having its sides creased in transverse lines *b b* between the notches *a a* to form flaps *c c c* which may be folded over, as indicated by the front flap *c* in Fig. 1 and as shown in Fig. 3 and at the bottom of Fig. 2, the notches *a a* being of such form that the edges of the adjacent flaps may come together or nearly together as shown in Fig. 1, or at least that they do not overlap.

B B are the lining strips consisting each of a strip of paper of such thickness as to permit it to be easily folded, of such length that it may surround the interior of the box and of such width or depth that one of its longitudinal margins may be pasted to and around that portion of the interior of the body of the box just within or beyond the creases *b b* which are made for the flaps, and that its outer edge may project beyond the said creases so far that it will fold in sufficiently far over the cavity of the box to make a good closure. The width or depth of the pasted margins of the strips B B within the body of the box is indicated between the creases *b b* and the lines *d d* which represent the inner edges of the strips. The said strips B B not only have their inner margins pasted to the interior of the box but they are also pasted to the flaps, so that when the said strips are folded in, the flaps turn in with them and make substantial corners all around the end of the box.

Either or both ends of the box may be constructed as above described, but in explaining the filling and closing of the box I will assume that both ends are so constructed. For filling such a box it is first held in any suitable manner while the lining strips are folded in from the four sides in succession according to the usual way of folding in such lining strips, as shown in Figs. 2 and 3, the flaps turning in with and over the folds of the lining strip. The last two folds *e e* of the lining are gummed or pasted at their tips or edges to make them adhere to the folds previously turned in and the bottom is thus completed. The box is set up on its closed end.

and filled. The lining strip at the upper open end is then folded in, the corresponding flaps turning in with it and the last folds are fastened by pasting or gumming as just described with reference to the other end.

What I claim as my invention is—

A paper box having end flaps separated from one another at the corners so as to fold inwardly at right angles to the body portion without overlapping, and a lining strip at-

tached to the interior of the body portion and to the interior of said flaps whereby the flaps will be turned inward with and by the folding in of the lining strip, substantially as set forth.

JOHN J. HOFFMAN.
